APPARATUS FOR WASHING CLOTHES

James B. Kirby, West Richfield, Ohio, assignor to
 The Apex Electrical Manufacturing Co., Cleve-
 land, Ohio, a corporation of Ohio, as trustee

Application March 13, 1944, Serial No. 526,154

1 Claim. (Cl. 68—148)

1

This invention relates to apparatus for washing clothes and more particularly an apparatus for controlling the fresh water supply in a domestic washing machine of the single tub washer-extractor type.

It is an object of the invention to provide a washing machine having a receptacle wherein the clothes are washed and centrifugally dried with means for introducing a fresh water supply and for recirculating the water supply during the laundry operations.

It is a further object of the invention to provide a machine, according to the preceding object, wherein the admission of fresh water supply is controlled by means operatively associated with apparatus for recirculating the wash water supply.

It is a further object of the invention to provide a washing machine with apparatus for controlling the fresh water supply and recirculating the wash water, wherein the admission of fresh water is interrupted by recirculation of the wash water.

Generally speaking the foregoing objects have been attained according to the present invention, by the use of a fresh water supply conduit having a normally open valve so arranged that the fresh water supply is directed into the receptacle employed for washing the clothes. A tub is arranged beneath the receptacle to collect water removed from the receptacle during washing, and such collected water is recirculated by a pump so as to discharge the recirculated water into the top of the container. The recirculation conduit is provided with a pressure sensitive element operatively connected to the normally open valve in the fresh water supply. When recirculated wash water is being directed into the top of the washing receptacle the pressure sensitive element acts to close the valve in the fresh water supply line. It is characteristic of the apparatus of this invention, that the admission of fresh water is unaffected by variations in pressure in the domestic water supply. This arrangement insures the provision of the proper amount of water for washing without regard to the pressure at which the water is admitted into the machine and without regard to the time required to admit such a supply of water.

With the above and other objects in view the invention may be said to comprise the apparatus for washing clothes as illustrated in the accompanying drawings hereinafter described and particularly set forth in the claim together with such variations and modifications thereof as will

2

be apparent to one skilled in the art to which the invention pertains. Certain features of my invention disclosed herein but not claimed in the present application are claimed in my application, Serial No. 619,849, filed October 2, 1945.

Reference should be had to the accompanying drawings forming part of this specification in which:

Figure 1 is a central vertical section through 10 a combined washer and extractor embodying the invention;

Figure 2 is a section taken on the line indicated at 2—2 in Fig. 1;

Fig. 3 is a section taken on the line indicated 15 at 3—3 in Fig. 2;

Fig. 4 is a vertical axial section through the receptacle supporting standard showing the receptacle drive mechanism on an enlarged scale;

Fig. 5 is an elevational view taken as indicated 20 by line 5—5 in Fig. 4;

Figs. 6 and 7 are top plan view and side elevation respectively of one of the washer vanes;

Fig. 8 is a top plan view of the machine with a portion broken away to show part of the housing 25 and washing receptacle in section;

Fig. 9 is an elevational view taken as indicated by line 9—9 in Fig. 8;

Fig. 10 is a section taken on the line indicated at 10—10 in Fig. 8; and

Fig. 11 is a section taken on the line indicated at 11—11 in Fig. 2.

In the accompanying drawings a machine designed to carry out the present invention is illustrated. In washing clothes by means of the present invention, the clothes are placed in a suitable container of the extractor type indicated generally by the reference character A which is mounted for rotational movement about a central axis a and also for an orbital movement in which the axis a of the container moves in an orbital path about an axis b that is out of alignment with the axis a. The axis a is so disposed with respect to the axis b that the orbital movement of the container is of small ambit, and the axis a is preferably at an angle to the axis b so that the receptacle rocks during its orbital movement. As herein shown the axis of rotation a intersects the orbital axis b at a small angle, the point of intersection preferably being near the center of gravity of the receptacle when loaded so as to maintain both a static and running balance and thereby minimize the vibratory effect of the orbital movement. The washing operation is performed by placing the clothes with water in the receptacle A and im-

parting orbital movement to the container about the axis *b* while the container is held against rotation about its axis of rotation *a*. The receptacle *A* is mounted within a suitable housing *B* and within the upper portion of an annular collection receptacle or tub *C*. During the washing operation water drains from the receptacle into the tub and is pumped back into the receptacle to maintain the proper amount of water in the receptacle for the washing operation.

The speed of orbital movement during the washing operation corresponds to the speed of rotation for extraction and is preferably at least 600 R. P. M. With an orbital movement at such high speeds some portions of the receptacle bottom are at every instant moving in a downward direction faster than the water and clothes can fall by gravity and other portions are moving up to slap against the falling body of water and clothes so that the mass of water and clothes is subjected to rapidly repeated pulsations at all points throughout the extent thereof.

The orbital movement of the receptacle tends to cause the liquid in the receptacle to flow circumferentially in the direction of orbital movement. This flow of the liquid is impeded by suitable vanes on the peripheral wall of the receptacle which engage with clothes and water and have a rubbing action against the clothes during their movements in the receptacle. The receptacle actuating mechanism is so disposed that the orbital movement is imparted to the receptacle while it is being held against rotation about its axis *a*. When the receptacle is released the torque that is imposed thereon by the orbital movement serves to rotate the receptacle about its axis and to accelerate the rotational movement uniformly so that the receptacle is brought to extracting speed without strain on the driving mechanism.

During the washing operation the clothes move outwardly along the bottom to the peripheral wall of the receptacle and simultaneously progress around the receptacle circumferentially. The engagement of the clothes with the vanes on the laterally and vertically rocking peripheral wall causes them to work their way up the wall and then to move back over the top of the body of water and clothes toward the center of the receptacle during their travel about the orbital axis. The rocking orbital movement imparted to the washing receptacle is very rapid and serves to effectively distribute the clothes throughout the body of water in the receptacle and subjects the clothes to continuous agitation and rubbing action against the peripheral vanes.

In the machine herein illustrated the housing *B* is of rectangular form and has a top *1* provided with a central opening closed by a suitable lid *2*, the tub *C* being supported within the housing on suitable brackets *3*. The tub *C* extends to the top of the receptacle and has an inturned splash flange *4* at its upper edge. The tub *C* has a central upright tubular wall *5* and is provided in its bottom with a segmental motor receiving recess *6*. The combined washing and extracting receptacle *A* is mounted within the upper portion of the tub *C*, being supported upon the upper end of a tubular standard *7* that is mounted within the interior tubular wall *5* of the tub. The standard *7* is supported centrally of the housing by four supporting legs *8* extending radially and downwardly beneath the tub *C* to the bottom of the housing at the four corners thereof where suitable nuts *9* on threaded foot

members *10* provide adjustable supports for the housing *B*. The inner ends of the supporting legs *8* are attached to a central ring *11* which serves as a support for the standard *7*.

The ring *11* is formed with an upright cylindrical body member *12* within which the lower end of the standard *7* is mounted, the member *12* having an inwardly extending supporting flange *13* at its lower end. The lower end of the standard *7* is positioned within the inner margin of the inwardly extending flange *13* and fitting upon the lower end of the tubular standard *7* there is a washer *14* which rests upon the flange *13*. Upon the washer *14* there is mounted a rubber ring *15* which is preferably of rectangular cross section and which fits upon the exterior of the standard *9* and within the interior of the cylindrical body *10* of the supporting ring. Upon the top of the rubber ring *15* there is mounted a washer *16* which has an internal diameter greater than the diameter of the tubular standard *7* and an external diameter such that it fits within the cylindrical member *12* of the supporting ring. The standard *7* has a peripheral flange *17* that rests upon the top face of the washer *16*, and on the top face of the flange *17* there is mounted a second washer *18* which may be a duplicate of the washer *16*. A rubber ring *19*, similar to the ring *15*, is mounted upon the top of the washer *18* and a washer *20*, which may be a duplicate of the washer *14*, is mounted upon the top of the rubber ring *19*. A clamping ring *21* is mounted upon the upper end of the member *12* and has a shouldered inner portion *22* that fits within the upper end of the cylindrical member *12* and bears against the washer *20*. The clamping ring *21* is held in place by bolts *23* that secure the same to the ring *11*. The tubular standard *9* is thus resiliently supported in the ring *11* by means of the rubber rings *15* and *19* and these rings are held securely in place by the confining washers *14*, *16*, *18* and *20* which prevent the corners of the soft rubber rings from being pinched between the standard and supporting ring. The standard *7* may have a resilient buffer ring *1a* mounted thereon which is engageable with the interior of the tubular wall *5* of the tub to limit lateral movements of the standard. The resilient mounting permits the standard *7* to have slight vertical and lateral movements with respect to the supporting frame, the resilient cushioning support and buffer serving as a damping means to check the transmission of vibrations to the supporting frame.

At the upper end thereof the standard *7* has a heavy collar *24* upon which is mounted a self aligning ball bearing *25* that has an outer race ring *26* mounted in the collar *24* and an inner race ring *27* that is secured to a tubular shaft *28* positioned within the tubular standard *7*, the inner race ring *27* being seated against the underside of an enlarged head *29* at the upper end of the tubular shaft *28*. The inertia of the collar *24* tends to impede lateral vibrations of the standard *7*.

The enlarged head *29* of the shaft *28* provides a support for a second ball bearing *30* that is mounted at a slight inclination to the ball bearing *25*. The ball bearing *30* has an outer race ring *31* that is seated in the enlarged head *29* of the shaft and held in place therein by a clamping collar *32* that is threaded upon the upper end of the head *29*. The bearing *30* has an inner race ring *33* that is secured to a supporting

block 34, the block 34 having a projecting flange 35 at its lower end upon which the race ring 33 is seated and the race ring 33 being clamped against the flange 35 by means of a circular flange 36 on a plate 37 that is attached to the central bottom member 38 of the receptacle A. A plurality of attaching screws 39 extend through the member 38 and plate 37 and are threaded into the block 34 to secure the receptacle to the block 34 and to clamp the race ring 33 against the flange 35 of the block. A dome-shaped shield 40 is mounted upon the bottom member 38 and covers the screws 39, the shield 40 being held in place by means of a center bolt 41 that is threaded into the block 34 at its lower end. The ball bearing 30 serves to rotatably support the receptacle A, the axis of the bearing being the axis *a* about which the receptacle may rotate and the axis of the tubular shaft 28 being the axis *b* about which the receptacle may move orbitally. The angle of inclination of the axis *a* with respect to the axis *b* is small. In the machine illustrated the angle is about four and one-half degrees. It is to be understood however that greater or less angularity may be desirable for machines of smaller or larger size or for machines operated at lower or higher speeds.

The tubular shaft 28 has a pulley 42 attached to its lower end, the pulley 42 being positioned beneath the lower end of the standard 9 and having a threaded hub portion 43 screwed into the lower end of the tubular shaft 28. The pulley 42 and shaft 28 are driven by suitable belt 44 that extends around the pulley 42, around a second driven pulley 45 and around a driving pulley 46 on the shaft of an electric motor 47. The shaft 28 is driven by the motor 47 at a speed at which the receptacle may be advantageously driven for the extracting operation. For extracting, the speed should be above 400 R. P. M., a speed of about 600 R. P. M. is preferred.

The motor 47 is adjustably mounted so that proper tension may be maintained upon the driving belt 44, the motor casing being provided with vertically spaced lugs 48 that receive between them an arm 50 formed integrally with one of the supporting legs 10, the lugs 48 being secured to the arm 50 by means of a vertical pivot pin 51 about which the motor may be swung to tension the belt. Any suitable means may be provided for holding the motor in adjusted position. As herein shown the motor casing has a lug 52 on the side thereof diametrically opposite the lugs 48 and 49, to which is pivotally attached a link 53 that is adapted to be adjustably secured to one of the supporting legs 8 to hold the motor in adjusted position, the link 53 being provided with a longitudinal slot 54 that receives a clamping bolt 55 that is screwed into the supporting leg 8.

Within the tubular shaft 28 there is mounted a shaft 56 which has an upper ball shaped end 57 that is received in a tubular projection 58 on the under side of the block 34. A pin 59 extends transversely through the ball-shaped end 57 and projects into vertical slots 60 formed in the socket 58, the ball socket and pin providing a flexible driving connection between the washing receptacle and the shaft 56. The shaft 56 has a ball-shaped lower end 61 that is located a short distance above the hub 43 of the driving pulley, the ball 61 fitting into an enlarged socket 62 in the upper end of a vertical lower shaft section 63 which extends downwardly through the pulley 42. A pin 64 extends through the ball end 61 and engages in vertical slots 65 in the socket 62, the

ball socket and pin forming a flexible connection between the upper and lower shaft sections 56 and 63. An oilless bearing sleeve 66 is interposed between the shaft section 63 and the hub 43 of the driving pulley and to the lower end of the shaft section 63 there is attached a brake drum 67. The drum 67 has a hub 68 keyed to the shaft 63 and mounted in a self-aligning bearing 69 that has an inner race ring 70 secured to the hub 68 and an outer race ring 71 mounted in a tubular flange 72 of a lower housing plate 73 that is cupped to enclose the brake drum 67 and provided with a peripheral flange 74 underlying the ring 71. The plate 73 is suspended from the ring 71 by means of bolts 75 and held in proper spaced relation with respect to the ring 71, by means of spacing sleeves 76 mounted on the bolts 75 and interposed between the plate 74 and the ring 71.

To insure proper alignment of the shaft 63 with the driving pulley 42 and the shaft 28, an additional ball bearing 77 is interposed between the lower end of the hub 43 and shaft 63. The mounting of the shaft section 63 in the hub of the pulley 42 maintains the shaft section 63 in axial alignment with the shaft 28 and the bearing 69 will permit the tubular shaft 28 and the sectional shaft mounted therein to rock slightly with respect to the supporting frame. Only slight vibratory rocking movements of the shafts and standard occur during operation of the machine and the amplitude of these movements is not sufficient to interfere with the operation of the driving belt.

During the washing operation the washing receptacle A is held against rotation and rotation of the shaft 28 causes the washing receptacle A to have an orbital rocking movement about the intersection of its axis *a* with the vertical axis *b* such that each point in the receptacle wall moves in an orbit of small circumference or ambit.

Points in the receptacle wall lying in a plane normal to the axis *a* at the intersection of said axis *a* with the vertical axis *b* will reciprocate vertically in an arc having its center at said point of intersection. The orbital center where the axes *a* and *b* intersect is located at a point above the bottom of the receptacle and below the top thereof. The orbital movement of the receptacle and the action of gravity upon the water causes a circumferential flow of water in the receptacle and the rapid oscillatory impulses serve to keep the clothes uniformly dispersed and distributed throughout the receptacle during washing. The speed of vertical oscillation is such that downward movements are faster than the movement of the water due to gravity so that the bottom of the receptacle slaps against the body of water and creates rapidly repeated pulsations throughout the body of clothes and washing fluid that causes the fabrics to be continually flexed while the washing fluid surges through the interstices thereof.

For holding the shaft 56 and the receptacle A against rotation, a brake band 78 surrounding the brake drum 67 has one of its ends anchored to the supporting plate 73 and its opposite end attached to an actuating lever 79 which swings on a vertical pivot 80. When the brake band 78 is applied, the brake drum 67 and the receptacle A connected to the drum through the shaft 56 is held against rotation so that an orbital rocking movement only is imparted to the receptacle A. When the brake band 78 is released, the shaft 56 and receptacle A are free to rotate and, upon release of the brake, the torsional thrust

exerted by the shaft 28 on the receptacle causes the receptacle to rotate with gradually increasing speed. With the shaft 28 driven at 600 R. P. M. the washing receptacle will attain a speed somewhat above 350 R. P. M. due to the torque applied to the container through the inclined bearing 30. For more effective extraction of liquid it is desirable that the receptacle be rotated at the full speed of the shaft 28 and to accomplish this result a suitable clutch mechanism is provided which serves to establish a direct driving connection between the receptacle and the shaft 28 to rotate the receptacle at full speed. The clutch mechanism is preferably automatic and controlled by the driven receptacle to operate when a predetermined speed of rotation is attained by the receptacle. As herein shown the pulley 42 is provided with a depending cylindrical flange 81 which serves as a clutch element and the upper face of the brake drum 67 is provided inwardly of the flange 81 with bosses 82 in which are mounted pivot pins 83 upon which clutch shoes 84 are mounted to swing into and out of engagement with the interior of the flange 8. Each of the clutch shoes 84 is normally held in retracted position with respect to the flange 81 by means of a coil spring 85 which is attached to one end to a lug 86 on the clutch shoe and at its other end to a post 87 attached to the brake drum 67. When the brake drum 67, which rotates with the receptacle A, attains a predetermined speed of rotation, the centrifugal force acting upon the clutch shoes 84 presses the shoes outwardly against the interior surface of the clutch element 81 so that torsional force is exerted upon the drum 67 and receptacle A. While the shoes 84 may permit some slippage when first engaged with the flange 81, the pressure of the shoes against the flange 81 is increased as the speed of the receptacle increases so that the receptacle is frictionally clutched to the rotating shaft 28 to transmit additional torque from the drive shaft.

The bottom member 38 of the receptacle A provides a support for the receptacle above its bottom and has a tubular wall 88 that encloses the upper end portions of the standard 7 and shafts 28 and 56. At its lower end the wall 88 terminates in an outwardly flaring downwardly inclined portion 89 to which the outer portion of the receptacle body is attached. The central plate 38 may be of relatively rigid construction but the body portion of the receptacle is preferably made of relatively light sheet metal such as sheet aluminum. The body portion of the receptacle has a lower section 90 that forms the outer portion of the receptacle bottom and which has a peripheral wall portion 91 that forms substantially the lower half of the peripheral wall of the receptacle. An upper section 92 attached to the top edge of the wall portion 91 forms the upper half of the receptacle wall, the upper section 92 being curved inwardly and terminating in a bead 93 that surrounds a central opening at the top of the receptacle that underlies the central opening in the top 1 of the housing. The lower section 90 of the receptacle wall has a plurality of small drain openings 94 in the bottom through which solid particles settling to the bottom of the receptacle are flushed during operation of the machine and a few perforations 94a in the side wall. The upper section 92 of the receptacle wall is, however, provided with more closely spaced perforations 95 through which suds may drain during the washing operations

and through which liquid may be forced during the extracting operation.

The inclined bearing 30 provides a drive connection between the shaft 28 and the receptacle A which is adapted to slip when there is a resistance to rotation of the receptacle. The torque transmitted from the shaft 28 through the inclined bearing 30 tends to cause the receptacle to turn bodily with the shaft 28. Whenever the resistance to rotation of the receptacle with the shaft 28 is sufficient to cause the receptacle to lag with respect to the shaft, the shaft begins to turn within the bearing 30 and the receptacle begins its pulsating movement. If the resistance to turning movement of the receptacle is sufficient it will be held against rotation and will move orbitally with the inclined bearing 30. If the resistance to rotation is less than that necessary to hold the receptacle against rotation the receptacle will turn about the axis b at a speed slower than the shaft 28 and will have simultaneously a rocking orbital movement. The receptacle A acts as a weighted member or flywheel mounted for rotation about either the axis a or the axis b or simultaneously about both axes. The inertia in starting will cause the speed of rotation about the axis b to be slow at the start and to gradually increase while the speed of oscillation decreases. A drive is thus provided, in which there is an automatically regulated application of torque.

Within the receptacle A, a series of elongated vanes 96 are detachably secured to the peripheral wall and short vanes 96a may be provided in the receptacle bottom, successive vanes 96a being preferably oppositely inclined. These vanes are preferably hollow and V-shaped in cross section. It has been found that the vanes 96 are most effective if disposed at an inclination. In the machine shown the rotation of the machine is counterclockwise and the vanes 96 are disposed at an inclination of approximately 38° with their upper ends in advance of their lower ends in the direction of rotation. It should be noted that the vane 96 extends above and below the normal plane above referred to which intersects the axes a and b at their point of intersection which is the center of orbital movement. By reason of their location on the peripheral wall of the receptacle, the vanes 96 have a compound oscillating movement. The oscillating vanes serve to greatly increase the agitation of the clothes and washing fluid and have a very effective flexing and scrubbing action upon the clothes. A complete oscillating movement is imparted to each vane upon each revolution of the shaft 28, and, since this shaft is rotated at a high speed such as 600 R. P. M., the oscillation of the vanes is extremely rapid. The effect upon the water and clothes during operation is to cause the clothes to move out to the peripheral wall of the receptacle to work up the vanes and to be moved inwardly toward the axis, the movement of the clothes during the washing operation being circumferentially and spirally in the receptacle.

To maintain the proper amount of liquid in the washing receptacle, means is provided for pumping water from the tub into the receptacle during the washing operation. As best shown in Fig. 3 the tub has an outlet 97 in its bottom that delivers into the central inlet of a suitable centrifugal pump 98 that is driven by the pulley 45 and that delivers the liquid through a flexible conduit 99 to a spout 100 positioned to deliver water into the open top of the receptacle A. A

fresh water delivery pipe 101 is mounted in the housing B and is adapted to be connected through a suitable hose to a water supply line. The delivery of water through the pipe 101 is controlled by a hand operated valve 102 and by a second normally open valve 103 that is so connected to a suitable solenoid 104 that it will be closed when the solenoid is energized. The solenoid 104 is controlled by a switch 105 that is operated by a Sylphon 106 connected to the spout 100. The spout 100 has a restricted outlet 107 so that when a full stream of water is delivered through the spout 100, there will be sufficient back pressure on the Sylphon 106 to move the switch 105 to closed position. When the switch 105 is closed by the Sylphon 106 the solenoid 104 is operated to close the valve 103 and stop the delivery of fresh water to the receptacle.

When the machine is started the valve 102 is opened to deliver water to the receptacle A and the motor 47 is started into operation to spin the receptacle. When sufficient water accumulates in the tub C to enable the pump 98 to deliver a full stream through the conduit 99 and spout 100 the switch 105 is closed by the Sylphon 106 and the delivery of fresh water is automatically stopped. In this way the proper amount of water for effective washing is supplied to the machine. If the amount of water originally delivered to the machine is not sufficient to maintain a full flow through the spout 100, reduction of pressure on the Sylphon 106 will permit the valve 103 to open momentarily to supply additional water.

A drain conduit 108 is also connected to the outlet of the pump 98 and this conduit is provided with a valve 109 that is operated by an arm 110 on a vertical shaft 111 that extends to the top of the housing and which is provided with a suitable handle 112 at the top of the housing by means of which it may be turned to open or close the drain outlet. In order to insure that the valve will be held either in the full open or in the full closed position, the handle 112 may have yielding engagement with the curved top of a latch plate 113 that bridges the space between the full open and full closed positions. The drain outlet 108 communicates with both the tub C and the delivery conduit 99 so that the conduit 99 and the spout 100 as well as the tub is drained when the drain valve is opened. The pump 98 rapidly discharges water from the tub through the drain outlet if the valve 109 is opened while the machine is in operation. If the valve is opened when the motor is stopped, the pump, being a conventional centrifugal pump, will permit drainage between its vanes.

The spout 100 is mounted upon the upper end of the conduit 99 to turn from a position in which it delivers water into the receptacle A to a position at which it delivers the water back into the tub C outside the periphery of the receptacle A. The spout 100 may be mounted in any suitable way to swing through the necessary angle. As herein shown, the spout 100 is attached to the upper end of a vertically disposed rotatable shaft 114 and also rotates on a centering pivot 115 attached to the top of the housing I in axial alignment with the shaft 114. The shaft 114 has an arm 116 at its lower end adjacent the bottom of the housing and the arm 116 is connected to a link 117 which has a curved end 118 pivoted to an arm 119 attached to a vertical operating shaft 120. The operating shaft 120 has a second arm 121 attached thereto to which is pivoted a

link 122 that has a curved end 123 attached to the arm 121, the link 122 serving to connect the shaft 120 with the brake operating lever 79. The link 122 is preferably extensible being formed of sections being connected by bolts 124 extending through longitudinal slots 125. The links 117 and 122 and arms 119 and 121 are so arranged that the shaft 120 has a limited rotational movement. Turning movement of the shaft 120 in one direction is limited by the link 122 and in the other direction by the link 117. The shaft 120 extends to the top of the housing and has a handle 126 by which it may be turned to actuate the brake band 78 and the spout 100. When the handle 126 is turned to a position to engage the brake band 78 with the brake drum 67, the spout 100 is moved to a position to deliver water into the receptacle A. When the handle 126 is turned to the opposite position to release the brake band 78 and permit rotation of the receptacle A, the spout 100 is automatically swung to a position to deliver water back into the tub beyond the periphery of the receptacle A.

Although the operation of the machine may be varied the preferred procedure will now be described. The clothes are placed in the washing receptacle, the lever 112 is moved to drain closing position, the lever 126 is moved to brake releasing position and the motor 47 is started into operation. The valve 102 is then opened to admit water to the receptacle A through the delivery pipe 101. Operation of the motor 47 with the brake 78 released causes the receptacle A to spin while the clothes are being saturated with the wash water. When sufficient water accumulates to the tub to enable the pump 98 to deliver a full stream through the spout 100, the valve 102 is automatically closed to stop the delivery of water to the machine.

By delivering the wash water to the machine while the receptacle is free to spin, the clothes are given a preliminary rinsing and the proper volume of washing fluid supplied to the clothes in the receptacle while the receptacle is free to rock or spin.

It should be noted that the automatic control of the delivery of water to the machine is in part dependent on the quantity of clothes in the machine, since the water required to saturate the clothes is retained in the receptacle A while sufficient water is accumulating in the tub C to permit a full stream to be delivered through the spout 100.

When the proper amount of liquid has been supplied to the machine and the delivery of water is stopped the lever 126 is shifted to washing position, setting the brake 78 to hold the receptacle against rotation and shifting the spout 100 to a position to deliver into the receptacle A. Soap powder is preferably placed in the receptacle A at this time and the washing operation is continued for a time sufficient to effect the cleaning of the clothes. Because of the extreme rapidity of the pulsations to which the clothes and washing fluid are subjected a very short period of time is required for the washing operation.

At the end of the washing period the valve 102 is closed, the lever 112 is shifted to drain opening position and lever 126 is shifted to extracting position in which the brake 78 is released and the receptacle A is allowed to spin. After a short period of extracting the valve 102 is opened to turn on the water supply. The water passing through the clothes in the spinning

receptacle and out through the drain will quickly carry off most of the suds remaining in the clothes. After this initial spin rinse, the lever 112 is moved to drain closing position and after the water supply is cut off by the solenoid 105, the lever 126 is moved to washing position and the clothes are subjected to a wash rinse for a short period of time. The lever 112 is then moved to drain opening position while the valve 102 is left for a short time to provide a final spin rinse. The valve 102 is then closed and the continued spinning of the receptacle extracts the water from the clothes.

The operation of the controls in the machine of the present invention is extremely simple, and, while the main control elements as herein illustrated are manual, it is apparent that the control devices shown are well adapted for automatic operation by suitable timing devices well known in the art.

It has been found that a full sized machine constructed substantially like that herein illustrated, having a diameter of about 22 inches, a depth of about 10 inches, and mounted to oscillate through an angle of about 9 degrees, efficiently washes eight pounds of clothes when pulsated at the rate of 600 times per minute. In this machine ten of the ribs or vanes 96 are provided and these vanes are inclined upwardly at about 38° in the direction of the rotation of the tubular operating shaft 28. The tubular shaft 28 is rotated counterclockwise at about 600 R. P. M. and the resultant pulsations cause the clothes to move outwardly from the hub of the container along the bottom, up the outer wall, back toward the center of the container and thence downwardly at the hub. In addition to the "roll over" movement above described the body of the clothes and washing fluid moves circumferentially in a counterclockwise direction in the receptacle so that the clothes move in a generally spiral path while they are being subjected to the pulsations of the washing fluid and the rapid rubbing and flexing action of the oscillating vanes 86.

Although the speed of operation of the machine renders it difficult or impossible to determine with exactness what takes place during washing, I believe that during the successive tilting of the receptacle the bottom thereof moves downwardly at a rate exceeding the rate at which the clothes and water fall freely due to gravity. I am aware that such rapid downward movement may create a vacuum and thus tend to pull the water and clothes downwardly. Thus there may result a rapid pumping action which flexes and unfolds the clothes during washing. This theory of a rapid pumping action is supported by the fact that numerous small geysers or jets of water appear at the upper surface of clothes and water during the washing.

The amplitude of vertical rocking movement of the receptacle A during the washing operation is determined by the inclination of the axis α and the diameter of the receptacle and the speed of rotation of the shaft 28 should be such that points in the receptacle bottom should move from their uppermost to their lowermost position in a time interval considerably shorter than that required for the clothes and washing fluid to fall the same distance by gravity so that at every instant a substantial portion of the bottom of the receptacle may be out of contact with the clothes and liquid and portions of the bottom throughout the circumference slap against the body of

liquid and clothes during each oscillation. In the machine above referred to, points in the outer portion of the receptacle bottom have a vertical movement of about 1 1/4" and the movement of such points from the uppermost to the lowermost position takes about one twentieth of a second when the shaft 28 is driven at 600 R. P. M. Since the fall of the clothes and water by gravity in the period of one twentieth of a second is less than one half inch, every part of the outer portion of the receptacle bottom may move into and out of contact with the body of clothes and washing fluid during each revolution of the shaft 28. In a machine such as herein illustrated the speed of rotation of the drive shaft should be at least 500 R. P. M. and is preferably 600 R. P. M. or higher.

The pulsating action on body of clothes and washing fluid effects a redistribution of the clothes in such manner that the load is evenly balanced throughout the washing operation and eccentric loading unfavorable to efficient extracting action is avoided.

When the brake 78 is released to start the extracting operation the spinning movement exerts a centrifugal force on the clothes tending to move them out to the periphery of the receptacle and this outwardly acting force together with the oscillating movements due to the lag of the receptacle A with respect to the drive shaft 28 causes the clothes to quickly move outwardly and upwardly to form a substantially uniform vertical layer of clothes against the interior of the peripheral wall.

The holes in the lower part of the container are of a size and number so related to the rate of delivery by the pump 98 to the receptacle that draining of the liquid is retarded sufficiently to maintain enough liquid in the receptacle to lubricate the clothes and permit the free flexing thereof, and the rolling and progressing movements above referred to. However, the liquid drains freely enough to avoid the retention of an excess of liquid in the receptacle.

Where, as herein illustrated, a machine of the present invention is mounted upon four supporting legs, a slight unevenness in a floor surface may cause the weight of the machine to be imposed upon three of the legs while the fourth leg is out of contact with the floor. With the machine so supported, a very slight force is required to rock the frame about two of its supports and impart slight vertical movements to the other two supports. Vibrations in the frame may thus cause vertical movements of opposite corners of the frame that will create noise and tend to cause the machine to creep on the floor surface. To eliminate vibration of the supports one of the screw feet 10 may be replaced with a self adjusting vibration damping foot member 130 such as shown in Fig. 11. The foot member 130 is in the form of a vertical rod which is slideable in the lower head 131 of a cylinder 132. The head 131 has a reduced extension 133 that passes through the leg 8 and has a threaded lower end to receive a nut 134 that clamps the head and the cylinder to the leg 8. The upper end of the cylinder 132 is closed by a cup shaped head 135, and the foot member 130 is pressed against the floor by a coil spring 136 that is interposed between a disk 137 engaging the lower end of the cup shaped head 135 and a piston 138 attached to the upper end of the foot member 130. The cylinder 132 is partially filled with liquid and a packing ring 139 in the head 131 held in place by a gland 140 prevents leakage of fluid through

the lower head. The disk 131 and the piston 138 are provided with small bleeder openings 141 and 142 and the liquid fills the cylinder to above the level of the disk 137. The spring 136 acts to maintain a downward pressure upon the foot piece 130 so that a substantial portion of the weight of the machine is always imposed thereon. Vertical movements of the foot piece 130 are impeded by the body of liquid due to the retardation of flow through the bleeder opening 141 into the space below the piston and through the opening 142 into the chamber above the disk 137. This retarding of the movement of the foot piece 130 serves to damp vibrations transmitted through the frame and eliminates the vibratory tapping of supporting members on the floor surface.

It is to be understood that variations and modifications of the specific device herein shown and described for purposes of illustration, may be made without departing from the spirit of the invention.

What I claim is:

In a washing machine, a washing receptacle having means therein to wash the clothes, and being apertured to facilitate the removal of water from the receptacle during washing, a tub beneath the receptacle to collect water removed therefrom during washing, means to control the introduction of fresh water supply for washing purposes and recirculate the said supply during

the washing operation, comprising; a fresh water supply conduit for delivering water to said machine, a first valve in said supply conduit, a normally open solenoid valve in said conduit, a pump to withdraw water from said tub, a conduit leading from said pump and terminating above said receptacle so as to discharge wash water withdrawn from the tub into said receptacle during the washing operation, a fluid pressure responsive element in said conduit adjacent the discharge end thereof and above the bottom of said receptacle, and means operatively connecting said element and said solenoid to close said solenoid valve in response to pressure in said conduit whereby the recirculation during washing is effective to prevent the introduction of additional fresh water supply.

JAMES B. KIRBY.
